THREE-COLOR MECHANICAL PENCIL

Russell N. Thatcher, New York, N. Y.

Application February 27, 1946, Serial No. 650,403

5 Claims. (Cl. 120—14)

1

This invention relates to a mechanical pencil, and one of its objects is to provide a pencil with a series of lead holding shanks and means for successively withdrawing the shanks and the leads from service position, and successively moving the shanks to service position, so that the colored lead desired may be placed in service position, and its location determined by means of an observation window and enamel on the lead shanks.

Another object of the invention is to provide a pencil barrel with a bearing through which the plurality of lead holding shanks extend, which is mounted to turn with the barrel, and a hollow screw which is carried by a tube mounted to turn in the barrel, and which is engaged by cams formed on the upper ends of the lead holding shanks, the cams being shifted successively by rotative action to sliding connection with a slotted tube disposed within the hollow screw, so that each lead holding shank may be propelled outwardly or inwardly through the tapered end of the pencil barrel.

With the above and other objects in view, the invention relates to certain new and useful constructions, combinations and arrangements of parts, clearly described in the following specification, and fully illustrated in the accompanying drawings, in which:

Fig. 1 is an enlarged longitudinal sectional view through the three color pencil.

Fig. 2 is a fragmentary side elevation showing the series of lead holding shanks and the bearing through which these shanks slide, the latter being shown in section.

Fig. 3 is a top end view thereof.

Fig. 4 is a perspective view of the hollow screw, showing the upper connecting tube in part section.

Fig. 5 is a side elevation of the slotted tubular guide.

Fig. 6 is a top end view thereof.

Fig. 7 is a fragmentary sectional view, showing the position of one of the cam lugs in the selector notch and with reference to the screw thread of the hollow screw.

Fig. 8 is a transverse sectional view through the assembled pencil, taken above the cam lugs.

Fig. 9 is a similar view, taken above the bearing.

Referring to the accompanying drawings, 5 designates a tubular pencil barrel, which may be

2

of cylindrical or hexagonal construction, and which is formed with a tapered forward end portion 6, which is provided with external screw threads engaged by the internally screw threaded lead guide 7.

10 In the barrel 5 a tubular bearing 8 is tightly fitted and soldered to the inner surface of the barrel 5, at a point approximately midway of the ends of the barrel. In this bearing a plug 9 is mounted to turn, and this plug is formed with a vertical slot 10 for each of the lead holding shanks 11, 12 and 13.

15 Each lead holding shank is approximately rectangular in cross section, and is formed on its forward end with a lead holding socket clutch 14, in which the lead stick 15 is tightly gripped, and which projects endwise of the socket clutch. The upper end of each lead holding shank is formed with an outwardly directed cam 17. Each cam 20 is formed with a rounded edge portion 17a and a straight edge portion 17b.

25 The plug 9 is formed with an upstanding central portion 9a and the flange 18a of the tubular guide 18 rests on this plug and is held central by the upstanding boss or central portion 9a.

30 The tubular guide is interlocked to the pencil barrel through its flange 18a, which is formed hexagonal for this purpose. This guide is formed with a longitudinal slot 19, which extends from the flange 18a, but does not pass through this flange, to the shoulder 20, which is located below the upper end of the guide. The slot 19 is widened above the shoulder 20, and one edge 19a of this slot is formed with a helical curve 19b, and the other edge 19c is formed with a knife edge 19d, which extends parallel to the length of the tubular guide 18, the knife edge 19d facing outwardly on the tubular guide, as shown in Fig. 6.

35 On the tubular guide 18 the hollow screw 21 is disposed, and the upper end of this hollow screw is fitted in the tube 22, which is disposed in the upper end of the barrel 5. The tube 22 is interlocked to the hollow screw by means of the indents 40 21a and 22a, which fit one within the other.

45 The tube 22 is provided with an internal bead or shoulder 22b, and projects above the upper end of the pencil barrel 5, to receive the rubber eraser 23. A cap 24 is fitted on the tube 22, and the lower edge of this cap is formed with a rising

bevel 24a, and the upper edge of the pencil barrel 5 is formed with a matching bevel 5a.

The upper end of each of the pencil lead holding shanks is sprung outwardly, as shown in Fig. 2. Each of the cam lugs is disposed at an incline with reference to the axis of the pencil. The cam lugs are moved successively into the narrower slot 19 by rotating the barrel while the friction cap 24 is held, or by rotating the friction cap while the barrel is held. By producing rotative movement so that the guide 18 moves in a right hand direction relative to the hollow screw, the cam engaged with the slot 19 will be shifted downward.

When any cam is propelled upwardly out of the slot 19 it will ride along the shoulder 20 and be moved into engagement with the knife edge 19d, and will be forced by this knife edge inwardly of the wall of the tubular guide 18. When the cam is further moved so that it will pass the helical edge 19b it will be forced downward back into the slot 19.

The rotation of the screw 21 with respect to the guide toward the right with respect to Figure 7 will raise the particular cam 17 in guide slot 19 up out of the slot to a point where it is above shoulder 20. At this point, recess 21b of the screw 21 will carry the cam to the shoulder. The recess 21b acts as a selection recess since it carries the cams around at the upper end of their stroke to positions where they successively engage the guide slot.

Selection of the wanted color lead is obtained through the selection recess or notch 21b of the hollow screw 21, which is located below the insert tube 22, and slightly above the plane of shoulder 20. When the cam lug is moved from the helically curved 19b it will snap through the slot 19 of the guide tube 18, and will be forced by the screw pressure of the hollow screw downwardly through the slot 19, so that the lead carried by the shank of the cam lug, will be moved through the lead guide at the forward end of the pencil barrel. This movement is aided by the free sliding action of the lead holding shanks through the guide plug 9. The inclined disposition of the cam lugs provides the desired bearing engagement with the helical threads of the screw, so that wear is taken up by the full width of the cam lug.

The pencil tube or barrel 5 is formed with a window 25 in the wall thereof, which is located below the bearing 8 and each of the pencil lead holding shanks is brightly enameled with a color to indicate the color of lead for which it is used.

The window 25 is shown at the side in Figure 1. Preferably it should be in line with the guide slot 19. But when the window is at the side, the lead holding shanks may be appropriately colored so that the color of the shank opposite the window will indicate the color of the lead aligned with the guide.

The drawings illustrate a pencil equipped with three pencil lead holding shanks, which may be supplied with red, black and blue colored pencil leads, or any other combination desired. For most purposes these three colored leads will serve.

The user of the improved pencil can quickly shift any lead from service position to an interior position, and shift the required colored lead to service position, operating the relatively rotative parts to produce the required outward or inward propulsion of the lead disposed in service position.

It is understood that various changes in the details of construction, their combination and arrangement, may be made, within the scope of the claims which define the invention.

Having described the invention, I claim as patentable:

1. A pencil having a barrel provided with a pencil guide on its forward end, a bearing in the barrel, a plurality of pencil lead holding shanks each being rectangular in cross section, a plug mounted to turn in the bearing and formed with a slot for the sliding movement of each of said shanks, a lead holding socket on the forward end of each shank, a tubular guide disposed on the bearing and interlocked to the barrel against relative rotative movement, said guide having a longitudinal slot widened at the upper end thereof, a hollow screw enclosing the tubular guide and provided with a selector notch formed in the screw thread thereof, and a tube having a friction fit in the barrel and coupled to the screw.

2. A pencil having a barrel provided with a pencil lead guide on its forward end, a bearing cup secured to the barrel within the same, a plug mounted to turn in the bearing cup and provided with a series of slots, a pencil holding shank slidable in each slot and held against relative rotative movement therein, a cam lug on the upper end of each shank, a tubular guide having a base flange interlocked to the pencil barrel against relative rotation and provided with a longitudinal slot extending from said base flange through the upper end thereof, the upper end of said slot being widened to provide a shoulder and a knife edge on one side thereof and a helically curved edge on the opposite side thereof, the upper ends of the shanks being sprung outwardly to cause said cam lugs to successively engage said shoulder, knife edge and helical edge and enter the longitudinal slot of the tubular guide, and a hollow screw having a friction bearing in the upper end of the barrel and enclosing the tubular guide and provided with a screw thread having a selector notch located adjacent to the wide end of said slot.

3. The construction set forth in claim 2, each of the shanks being colored to designate the color of the pencil lead it holds and the wall of the barrel having a window for observing the color of said shanks.

4. A writing instrument having a barrel and a plurality of marking members; said barrel being provided on its forward end with a marking member guide, a bearing cup secured to the barrel within the same, a plug mounted to turn in the bearing cup and provided with a series of slots, a marking member retainer slidable in each slot and held against relative rotative movement therein, a cam lug on the upper end of each retainer, a tubular guide having a base flange interlocked to the barrel against relative rotation and provided with a longitudinal slot extending from said base flange through the upper end thereof, the upper end of said slot being widened to provide a shoulder and a knife edge on one side thereof and a helically curved edge on the opposite side thereof, the upper ends of the retainers being sprung outwardly to cause said cam lugs to successively engage said shoulder, knife edge and helical edge and enter the longitudinal slot of the tubular guide, and a hollow screw having a friction bearing in the upper end of the barrel and enclosing the tubular guide and provided with a screw thread having a selector notch located adjacent to the wide end of said slot.

5. A writing instrument having a barrel and a plurality of marking members, said barrel provided with a marking member guide on its for-

ward end, a bearing in the barrel, a plurality of marking member retainers each being rectangular in cross-section, a plug mounted to turn in the bearing and formed with a slot for the sliding movement of each of said shanks, a marking member holder on the forward end of each retainer, a tubular guide disposed on the bearing and interlocked to the barrel against relative rotative movement, said guide having a longitudinal slot widened at the upper end thereof, a hollow screw enclosing the tubular guide and provided with a selector notch formed in the

screw thread thereof, and a tube having a friction fit in the barrel and coupled to the screw.
